DOOR HINGE LOCATING AND MARKING
GAUGE

Guido F. Giannini, North Haven, Conn.

Application April 27, 1948, Serial No. 23,471

11 Claims. (CL 33—197)

1

This invention relates to door hinge locating and marking gauges and more particularly to a gauge of this nature having in its structure means whereby the width, length and thickness of the cuts in a door and in a door frame to receive the hinge flaps may be accurately and conveniently marked.

When hanging a door in a door frame, the door is first fitted to the opening in the frame, after which the location of the hinges is ascertained and marked on the door and on the door frame. Considerable time is consumed and labor is expended in locating the cuts in which the hinge flaps are to be seated in both the door and the door frame when the usual carpenter's scale, squares, thickness gauges, and straight edges are used. Even when care is used in making measurements inaccuracies occur which are apt to require replacement of material, or patching at the cuts.

To avoid the above disadvantages and to locate the cuts for the hinge flaps required in both the door and door frame expeditiously and without the necessity of a plurality of measurements it is contemplated as objects of this invention to provide a gauge whereby, when the door is once fitted to the frame, the frame and door may be marked simultaneously to show the desired location of the hinges, and then to mark the door and door frame, after separating them, for the correct location of the hinge flaps on both the door and door frame and to mark the door and door frame for the correct length, width and depth of the cut to receive the hinge flaps, by the use of the same gauge.

Another object is to provide a hinge locating and marking gauge of the above nature on one piece of material, and of such form that it may be conveniently carried in the pocket of the user's work-clothing.

A further object is to provide a door hinge locating and marking gauge which will be relatively inexpensive to manufacture, simple in construction, practical and very efficient, accurate, and durable in use.

With these and other objects in view, which will appear as the description proceeds, there has been illustrated in the accompanying drawings one form in which the invention may be embodied in practice.

In the drawings:

Figure 1 is a view of a door and its frame in fitted relation and showing the use of the hinge locating gauge of this invention in position to simultaneously mark the door and frame at the desired points to locate one of the hinges;

Figure 2 is a face view of the hinge locating gauge of this invention, the gauge being shown in position on the edge of a door for use in marking the length of the cut to receive the hinge flap;

2

Figure 3 is a side view of the gauge looking in the direction of arrows 3—3 of Figure 2;

Figure 4 is a face view of the gauge, the gauge being shown in position on the edge of the door for use in marking the width of the cut to receive the hinge flap;

Figure 5 is a side view of the gauge looking in the direction of arrows 5—5 of Figure 4;

Figure 6 is a side view of the gauge, it being shown in position with respect to a door for use in marking the depth of the cut for receiving the hinge flap;

Figure 7 is a face view of the gauge, it being shown in position on the door frame for marking the length of the cut for receiving the hinge flap;

Figure 8 is a side view of the gauge looking in the direction of arrows 8—8 of Figure 7;

Figure 9 is a face view of the gauge, it being shown in position on the door frame for use in marking the width of the cut for receiving the hinge flap;

Figure 10 is a side view of the gauge looking in the direction of arrows 10—10 of Figure 9;

Figure 11 is a side view of the gauge, it being shown in position with respect to the door frame for use in marking the depth of the cut for receiving the hinge flap;

Figure 12 is a perspective view of one face of the gauge;

Figure 13 is a perspective view of the other face of the gauge; and

Figure 14 is a rear end view of the hinge locating gauge looking in the direction of arrows 14—14 of Figure 13.

Referring now to the drawings wherein like reference numerals designate like parts throughout the several views, the reference numeral 11 denotes a door frame and the reference numeral 12 denotes a door, shown in Figure 1 as fitted together ready to have hinges applied thereto. A hinge locating and marking gauge embodying the principles and features of this invention is shown at 13 positioned in respect to the door 12 and frame 11 to locate and mark them by nicks, or indentations, as indicated at 14, Figure 1.

The hinge locating and marking gauge 13 of this invention is preferably made of sheet metal and is generally in the form of a flat plate having a body portion 15 presenting a thin front edge 16. A short flange 17 is provided on each side edge 18 and 19 of the plate body portion 15. The flanges 17 are spaced inwardly from the front edge 16 and extend from the top surface of the portion 15 substantially at right angles thereto. The front end 21 of the flanges 17 is inclined upwardly and rearwardly and preferably is sharpened. A flange 22 is provided on each side edge 18 and 19 of the plate portion 15. The flanges 22 are spaced inwardly from the front edge 16, an amount equal to the spacing of the

flanges 17, and extend from the bottom surface of the portion 15 substantially at right angles thereto. The front end 23 of the flanges 22 is inclined downwardly and rearwardly and preferably is sharpened. The flanges 22 extend rearwardly along the side edges 18 and 19 to a forwardly directed shoulder 24, which is formed on and extends across the body portion 15 at right angles to the edges 18 and 19.

The width of the body portion 15 from the side edge 18 to the side edge 19 is substantially equal to the length of the flaps of a butt hinge to be applied to the door 12 and door frame 11. Thus by locating the gauge the desired amount from the top and bottom of the door 12 previously fitted to the frame, and inserting the thin edge 16 between the door edge and the adjacent edge of the door frame, as indicated in Figure 1, and then pressing the gauge toward the door, the sharpened front end edges of the flanges 17 and 22 will mark the extent of the length of the hinge flap simultaneously on both the door and the door frame by making the nicks 14, Figure 1.

After marking the door 12 and frame 11 by nicks, or indentations 14, the door 12 is removed from the frame 11 and positioned to present its hinge edge 25 as in Figure 2. The gauge 13 is then laid upon this door edge 25 with the shoulder 24 engaged against the front, or back, surface of the door and the flanges 22 engaged against the surface of the door hinge edge 25 at the nicks 14. By using the flanges 22 as guides, lines 26 may be scribed across the door edge 25, see Figures 2 and 3, by any pointed member.

The amount the hinge flap is set in from the front surface of the door is next gauged and marked, see Figures 4 and 5. A flange 27, extending inwardly from the rear edge 28 of the body portion 15 and parallel with the side edge 18, is adapted to be engaged against the rear surface of the door. The flange 27 is spaced away from the edge 18 the proper amount to cause the sharpened edge of a lug 29 to engage and mark a line 31 between the lines 26 on the door edge 25 by drawing the gauge lengthwise along the door 12 as indicated by arrow 32 in Figure 4. A portion 33 of the body portion 15 extends beyond the side edge 19 and by engaging this extended portion 33 against the hinge edge 25 of the door the sharpened edge of a lug 34 is spaced properly from the edge 25 to scribe a line (not shown) defining the depth of the cut to receive the hinge flap, see Figure 6. The door 12 is now gauged and marked, and is now ready to have the hinge flap recesses cut therein, which will be properly located and of the determined length width and depth.

The gauge 13 is now positioned as in Figures 7 and 8 with the front edge 16 abutted against the outer edge 35 of the door stop strip 36, a part of the door frame 11, and with the flanges 22 resting upon the hinge receiving surface 37 of the frame 11 at the nicks 14. Lines 38 may now be scribed across the surface 37, see Figure 7, using the flanges 22 as guides for the scribing tool. The amount the inner edge of the hinge flap sets away from the edge 35 of the stop strip 36 is now gauged and marked by engaging the side edge 18 against the strip edge 35, see Figures 9 and 10 so as to locate the sharpened edge of a lug 39 away from the strip edge 35 the proper amount. The gauge 13 is now drawn along the stop strip edge 35 in the direction of arrow 41, Figure 9, to cause the lug 39 to scribe a line 42 between the lines 38. The amount the line 42 is spaced from the stop strip edge 35 is slightly more than the

amount the line 31 is spaced from the back surface of the door 12 to allow clearance when the door swings on the hinges. To obtain this difference in dimensions the flange 27 is spaced from the side edge 18 a slightly lesser amount than the lug 39 is spaced from the side edge 18, see Figures 5 and 10. The extended portion 33, of the gauge, is now laid upon the surface 37 with the lug 34 engaging the edge of the surface 37, see Figure 11 to scribe a line (not shown) defining the depth of the cut to receive the hinge flap.

The gauge 13 is preferably provided with a thickened rear portion 43 to facilitate holding it during the gauging and marking of the guide lines. This thickened portion may be formed by bending the rear portion of the plate 15 over and back upon itself to form the hollow boxlike portion 43. The shoulder 24 is assisted in its locating, or squaring, operation by the front end of the flange 27 which terminates at the shoulder 24, and a short flange 44 extending downwardly from the bottom of the plate in alignment with the shoulder 24 starting from the side edge 19.

The device of this invention is particularly useful and time saving in home building wherein the same size and style of hinges are used for all of the interior doors, and thus the dimensions to be gauged, and the outline of the hinge flap receiving cuts to be defined, will be the same. All gauging and marking means are conveniently arranged and associated in one unit which is substantially flat and light in weight and thus may be readily carried by the workman in a pocket. Having the various gauging and marking means permanently set in respect to the required dimensions for the hinge to be installed, no time and labor is required and lost in making adjustments.

While there has been shown and described herein a preferred form of the invention, it will be understood that the novel features and principles of this invention may be embodied in other specific forms without departing from the spirit and essential attributes thereof, and it is therefore desired that the present embodiment be considered in all respects as illustrative, and not restrictive, reference being had to the claims rather than to the foregoing description to indicate the scope of the invention.

Having thus fully disclosed the invention, what is claimed as new and for which it is desired to secure Letters Patent, is:

1. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, and a shoulder extending across the plate from the rear ends of the second mentioned flanges, parallel to the front edge of the plate and substantially at right angles to the bottom face of the plate.
2. A door hinge locating and marking gauge comprising a flat rectangular plate of sheet metal

5

having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a short flange spaced inwardly from one side edge of the plate, and extending rearwardly from adjacent the rear end of the second mentioned side flange to the rear edge of the plate and substantially at right angles to the bottom face of the plate, and a sharpened edged lug extending at right angles from the said side edge of the plate and parallel to the said short flange.

3. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a sharpened edged lug spaced inwardly from one side edge of the plate, adjacent the rear edge of the plate and parallel to the said side edge of the plate.

4. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a short flange spaced inwardly from one side edge of the plate, and extending rearwardly from adjacent the rear end of the second mentioned side flange to the rear edge of the plate and substantially at right angles to the bottom face of the plate, a sharpened edged lug extending at right angles from the said side edge of the plate and parallel to the said short flange, a sharpened edged lug spaced inwardly from the said side edge of the plate, adjacent the rear edge of the plate and parallel to the said side edge of the plate, the amount the last mentioned short flange is spaced from the side edge of the plate being less than the amount the spaced inwardly sharpened lug is spaced from the same side edge of the plate.

5. A door hinge locating and marking gauge

6

comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a shoulder extending across the plate from the rear end of the second mentioned flanges, parallel to the front edge of the plate and substantially at right angles to the bottom face of the plate, a short flange extending outwardly from the bottom face of the plate and along the same in alignment with the said shoulder from one side edge of the plate, and a flange spaced inwardly from the other side edge of the plate and extending from the said shoulder to the rear edge of the plate.

6. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a shoulder extending across the plate from the rear end of the second mentioned flanges, parallel to the front edge of the plate and substantially at right angles to the bottom face of the plate, a short flange extending outwardly from the bottom face of the plate and along the same in alignment with the said shoulder from one side edge of the plate, a short flange spaced inwardly from the other side edge of the plate, and extending rearwardly from the said shoulder to the rear edge of the plate and substantially at right angles to the bottom face of the plate, and a sharpened edged lug extending at right angles from the said last mentioned side edge of the plate and parallel to the said last mentioned short flange.

7. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a shoulder extending across the plate from

the rear end of the second mentioned flanges, parallel to the front edge of the plate and substantially at right angles to the bottom face of the plate, a short flange extending outwardly from the bottom face of the plate and along the same in alignment with the said shoulder from one side edge of the plate, a short flange spaced inwardly from the other side edge of the plate, and extending rearwardly from the said shoulder to the rear edge of the plate and substantially at right angles to the bottom face of the plate, a sharpened edged lug extending at right angles from the said last mentioned side edge of the plate and parallel to the said last mentioned short flange, and a sharpened edged lug spaced inwardly from the last mentioned side edge of the plate, adjacent the rear edge of said last mentioned side edge plate and parallel to the edge of the plate the amount the last mentioned short flange is spaced from the said last mentioned side edge of the plate being less than the amount the spaced inwardly sharpened lug is spaced from the same side edge of the plate.

8. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a sharpened edged lug extending outwardly from a side edge of the plate in alignment with one face of the plate, and an extension protruding from the top face of the plate, parallel with and spaced from said lug.

9. A door hinge locating and marking gauge comprising a flat rectangular plate of sheet metal having top and bottom faces a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, and a shoulder extending across the plate from the rear end of the second mentioned flanges, parallel to the front edge of the plate and substantially at right angles to a face of the plate, a sharpened edged lug extending outwardly from a side edge of the plate in alignment with one

face of the plate, and an extension protruding from the other face of the plate, parallel with and spaced from said lug, said extension extending from a face of said plate opposite the face from which said shoulder extends, and with its front end in alignment with said shoulder and extending to the rear edge of said plate.

10. A door hinge locating and marking gauge comprising a flat rectangular plate of sheet metal having a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a sharpened edged lug extending outwardly from a side edge of the plate in alignment with the bottom face thereof, and an extension protruding from the top face of the plate, parallel with and spaced from said lug.

11. A door hinge locating and marking gauge comprising a flat rectangular plate of sheet metal having a thin front edge, and side edges extending rearwardly therefrom substantially at right angles thereto and spaced apart an amount substantially equal to the length of the flaps of the hinge being located, a short flange with its front edge spaced rearwardly from the front edge of the plate and extending rearwardly along each of the side edges and substantially at right angles to the top face of the plate, another flange with its front edge spaced inwardly from the front edge of the plate and extending rearwardly along the greater part of the length of each of the side edges and substantially at right angles to the bottom face of the plate, a sharpened edged lug extending outwardly from a side edge of the plate in alignment with the bottom face thereof, and an extension protruding from the top face of the plate, parallel with and spaced from said lug, said extension having its front end in alignment with said shoulder and extending to the rear edge of said plate.
